ANTHONY R. DYETT, OF NEW YORK, N. Y.

Letters Patent No. 74,824, dated February 11, 1868.

IMPROVEMENT IN WINDOW-SASH STOPS.

The Schedule referred to in these Letters Patent and making part of the same.

TO ALL WHOM IT MAY CONCERN:

Be it known that I, ANTHONY R. DYETT, of the city, county, and State of New York, have invented a new and improved Adjustable Lock for Car and other Windows, &c.; and I do hereby declare that the following is a full, clear, and exact description thereof, which will enable others skilled in the art to make and use the same, reference being had to the accompanying drawings, forming a part of this specification.

This invention relates to an improved adjustable lock for car and other windows, and is applicable to sliding shutters and similar guillotine arrangements.

It consists of two bolts, connected by toggle-levers, pivoted at their extremities, and disposed on the lower bar or other appropriate portion of the guillotine-sash or shutter. The bolts set into a rack in the window-frame, thereby holding the sash or shutter in any desired position. The bolts are held to their places in the rack by means of two wedges, which fit in the angles formed by the connection of the toggle-levers to each other, the wedges being held home to the angles by a spring fastened to them. The spring might, however, be placed laterally, and the wedges fit into the side angles, or the wedges may be replaced by a bar or plate. To shoot back the bolts, the spring is compressed, when, the wedges being drawn towards each other, springs, acting on the outside of each arm of the toggle-levers, press them together, drawing the bolts attached to their joints out of the racks. In the accompanying drawings—

Figure 1 represents a front view of a guillotine-sash having my improved adjustable lock attached on the front part of the lower bar thereof, the top plate removed in order to exhibit the details of my invention.

Figure 2 is a detail view of the working parts of my invention.

Similar letters of reference indicate corresponding parts.

A A is the window-frame, and B the sash, and in the present instance the lock is disposed in front of the lower bar of said sash, but it may be placed on the upper bar, or concealed within the timber, and in practice it is desirable that the working parts of my lock should be disposed within the sash or otherwise protected, as by a plate or cover over the same. C C' are two bolts, pivoted to the toggle-levers D D' at d d', and which, shooting into the racks H H', attached to or countersunk in the bead or side of the frame, hold the sash in any desired position. When the lock is disposed outside the frame, it will be necessary to provide guides c c' for the bolts C C', but when the fastening is disposed within the timber of the sash, as the bolts will be confined by the grooves in which they run, the guides c c' may be dispensed with. The toggle-levers D D' are connected together at d'' and d''', and are kept extended by the wedges E E, which are kept apart and held to the angles d'' and d''' by the spring F, which is of sufficient power to overcome the outside springs J J'. It is desirable that the first-mentioned spring, which may be in one or two pieces, should be held about the middle, so as to operate with equal force on both ends of the levers, and in the present instance this is effected by a plate, g, fixed to the top plate G, and which passes into and holds the spring. It is not, however, essential so to hold the spring F. The sash being held in any position by the bolts C C', which secure in the racks H H', to operate the same, so as to open or close the sash, the thumb-pieces e e are pressed together, when the wedges E E compress the spring F, and leaving the angles d'' and d''', enable the springs J J' to operate on the levers d d', and withdraw the bolts from the racks H H'. When the sash has reached its desired position, simply releasing the thumb-pieces e e enables the spring F to drive the wedges into the angles, shooting the bolts into the rack, and holding the sash, as desired. In the present instance the racks H H' have an upward slope, and the bolts C C' are bevelled at their free ends, so that the sash may be raised, without operating the spring, by simply pressing upwards, but it is readily seen that the rack and bolts may be so constructed (as by making the ends of the bolts C C' and the rack-teeth square) as to hold the sash from being raised, as well as from falling, except by operating the springs, thus preventing a window or shutter to which my lock is attached from being opened from the outside.

By the use of this lock the sash is held evenly, and prevented from jamming, as happens with all fasteners which are applied only to one side. The sash also may be inserted so loosely in the frame that no swelling in wet weather shall make it jam, and so that it may be easily and readily raised, while cords, pulleys, and

balance-weights, continual sources of annoyance and expense in guillotine-windows and shutters, are entirely dispensed with.

Having thus described my invention, what I claim as new, and desire to secure by Letters Patent, are—

1. The bolts C C', in combination with the toggle-levers D D', substantially as and for the purposes specified.

2. The said toggle-levers, in combination with the wedges E E', or their equivalents, substantially as and

for the purposes above described.

3. The said toggle-levers, in combination with the springs J J', substantially as described.

The above specification of my invention signed by me, this nineteenth day of November, 1867.

A. R. DYETT.
